DESIGN FOR A DISPLAY STAND FOR SPECTACLES OR THE LIKE

Patrick Gribben, Woodside, N. Y.

Application July 2, 1940, Serial No. 93,396

Term of patent 7 years

To all whom it may concern:

Be it known that I, Patrick Gribben, a citizen of the United States, residing at Woodside, in the county of Queens and State of New York, have invented a new, original, and ornamental Design for a Display Stand for Spectacles or the like, of which the following is a specification, reference being had to the accompanying drawing, forming part thereof.

I claim:

The ornamental design for a display stand for spectacles or the like, as shown.

PATRICK GRIBBEN.
